UNITED STATES PATENT OFFICE.

JACOB S. LAUTERBACH, OF NEW YORK, N. Y.

BOX.

956,859.

Specification of Letters Patent.

Patented May 3, 1910.

Application filed September 2, 1909. Serial No. 515,856.

To all whom it may concern:

Be it known that I, JACOB S. LAUTERBACH, a citizen of the United States, and a resident of the borough of the Bronx, city and county of New York, State of New York, have invented a new and useful Improvement in Boxes, of which the following is a specification.

My invention relates to boxes of paste board, paper, fabric and the equivalent. Such boxes are commonly formed from sheet materials and held in shape by means of paste, glue or other cement and are used to contain candies, cigars, laces and a wide range of other commodities. Such boxes as generally used may be opened, their contents removed, and then refilled. In the case of manufacturers using a distinctive style of box with distinctive marking said box may, after it has become associated with said manufacturer, be refilled with other and cheaper goods of another make to the obvious loss and disadvantage of the original manufacturer.

One of the objects of my invention is to provide a non-refillable box in which such fraudulent substitutions cannot take place.

Another object of my invention is to provide a box which may readily and quickly be made smaller as its contents are used. This not only does away with the superfluous volume included in a box whose contents are insufficient to fill it, but also avoids the necessity, when a box is to be carried a considerable distance, as in a trunk or otherwise, of stuffing said unused volume with something to prevent the contents shifting and becoming injured.

The exact character of my invention will be best understood by referring to the drawing accompanying and hereby made a part of this specification, in which—

Figure 1 represents a longitudinal section of a preferred form of my invention taken along the line 1—1 of Fig. 4; Fig. 2 represents a transverse sectional elevation taken along the line 2—2 of Fig. 4; Fig. 3 represents an end elevation taken from the right of Fig. 4; Fig. 4 represents a plan view of my improved box; and Fig. 5 is an enlarged sectional detail taken along the line 5—5 of Fig. 4.

Referring to the drawing A is the lid and B the body of the box. This body, although it appears when finished like an ordinary box body is in reality made up of two parts,

a lower part C consisting of the bottom α having joined thereto in the usual fashion the side and end walls b and an upper portion D comprising side and end walls only c . These side and end walls c of this upper portion are exactly the same as to length as the corresponding walls b of the lower portion but their width may be anything desired said width determining the height of the section.

In assembling the body B, I place the upper portion D upon the lower portion C and then, at each end within said lower portion, insert supporting pieces d which may or may not run clear across the box and which are preferably cemented thereto and the top of which is coincident with or slightly below the top of the end walls b . I have shown the supporting pieces d at the ends of the box only, but I may, if I choose, have these at the sides as well, or at the sides only and not at the ends. Upon these supporting pieces I place a partition wall E which has been cut to fit within the box body. Before inserting the partition, I lay about its periphery a fine wire F one end of said wire being formed into a loop or knot e and thrust into the edge of the partition E near one corner; the purpose of this loop or knot is to provide an easy and effective fastening means for the end of the wire. At each corner of the partition the edge thereof is slightly split so as to allow the wire to lie well inside the boundary of said corner. The free end of said wire after being taken completely around the partition wall, is projected outwardly and formed into a ring f .

The partition wall being in place on its supports d , the outside of the box is covered with paper or other fabric g cemented thereon in the usual way after which the paper h is also cemented upon the top of the partition wall and against the inside of the top section in the angle formed by the partition and said top section; the paper h being fastened snugly to both the walls c and the partition E holds the partition firmly in place and seals the compartment formed by it and the lower body portion C. The paper h although shown in the drawings as running along the four side walls of the box need only run along opposite walls or portions of said walls the purpose of said paper being only to fasten the partition in place and to seal the lower compartment.

In cementing on the outer paper h the

free end of the wire F is passed through said paper so as to leave the ring f on the outside thereof; to avoid tearing the paper this ring may best be formed after the paper h has 5 been cemented in position and the wire f passed therethrough. Preferably, also, the top body portion D may be very slightly spaced from the bottom portion C before said paper is laid on.

- 10 To use my improved box the lower section C of the box body is filled before placing the partition E and performing the other just described operations. The upper portion of the box is then filled and the lid A put in 15 place as usual. The box being thus filled, to use the same the lid is removed in the usual way and the contents of the upper section are first removed. To get out the contents of the lower section the wire loop f is taken between thumb and finger and pulled outwardly, when it will rip the outer paper h around the entire periphery of the box until the fixed loop e is reached, thus cutting away 20 entirely the upper body section D and opening 25 the lower closed compartment. The lid A may now be used in connection with this lower compartment to constitute a complete box just as it was used before the box body was divided.
- 30 It will be seen that the partition E not only serves as a separating wall but also to retain the wire in position adjacent to the weakened portion of the body walls. The corners of said partition wall also serve as 35 braces to hold the wire against the interior of the box body and make it impossible to pull the wire inwardly thereby avoiding ripping the paper g and dividing the box body. By reason of this bracing function 40 the wire F, when the ring f is pulled outwardly, tends to follow the dividing line between sections C and D completely around the box ripping the paper g as it goes and perfectly separating the two portions from 45 one another.

I have shown my improved box as having only one closed compartment *i. e.* as including only one detachable section to be ripped away. But it is obvious that, without departing from the spirit of my invention, I 50 may have any desired number of closed compartments and detachable sections by simply building up with additional partitions, top sections, wires, etc. as above described. 55 Each partition would require to be independently supported by pieces d and sealed by papers h but only one outside paper g would be required for any number of sections. 60 For many purposes my improved box will be found useful without the partitions. Thus *e. g.*, a box used in carrying candy, cigars, crackers and fragile materials generally may have section after section ripped off as the 65 contents are gradually removed, the lid be-

ing replaced upon the box body remaining. Substantially little free space need ever be left in the box, therefore, so that the contents are unable to shake about and become injured or destroyed. When it is desired to 70 thus use my invention braces of paste board, wood or other material may be placed within and at the corners of the box to hold the wire F in place and insure its following around the weakened lines of the box when 75 pulled outwardly; after a section has been ripped away the upwardly projecting ends of these braces may be broken off with the fingers or pulled away bodily from the inside of the body wall. 80

Instead of making my improved box of paste board with overlaid paper as described, I may for many purposes, especially when the partition walls are absent, use stiff paper or cardboard and in such case the 85 weakened lines along which the sections are to be divided may be impressed upon said cardboard in the well known manner. With such boxes, also, a stout thread may be substituted with advantage for the wire ordinarily used, the end of said thread being provided with a knot, ball, button or similar terminal. 90

Many other variations of detail may be employed within the scope of my invention 95 which I have defined in the following claims:

1. In a box of the class described the combination of a body having a weakened intermediate portion, a partition within said body, and a wire supported upon said partition adjacent to said weakened portion adapted to divide said body along said weakened portion, as and for the purpose described. 100

2. In a box of the class described the combination of a body, a partition within said body extending to the walls thereof so as to constitute one side of a closed compartment within said body, and a wire supported by said partition near the edges thereof said partition having one of its ends attached inside the body and its other end projecting through a body wall, said wire being adapted to cut through the body walls adjacent thereto when the outside end of said wire is 110 pulled outwardly, substantially as and for the purpose described. 115

3. In a box of the class described the combination of a body provided with walls having weakened lines, a partition within said body having its edges adjacent to said weakened lines so as to form a closed compartment within said body, and a wire supported by said partition arranged between said partition edges and the body walls 120 adapted to divide said walls along said weakened lines substantially as and for the purpose described. 125

4. In a box of the class described the combination of a body provided with walls hav-

ing weakened lines, a partition within and attached to said walls having its edges adjacent to said weakened lines, supporting means for said partition, and a wire attached 5 to and bordering the edges of said partition with one end of said wire outside of said box, said wire being adapted to divide said body walls along said weakened lines when pulled outwardly, substantially as and for 10 the purpose described.

5. In a box of the class described, the combination of a body provided with walls each of which has a weakened line, said lines all lying in the same plane, a wire arranged

within said body so as to be adjacent to each 15 weakened line, one end of said wire being attached inside said body and its other end projecting outwardly through a body wall, and means to support said wire and to resist its inward pressure when its projecting end 20 is pulled, as and for the purpose described.

In witness whereof, I have hereunto set my hand in the presence of two subscribing witnesses.

JACOB S. LAUTERBACH.
